UNITED STATES PATENT OFFICE.

ALBERT E. WEAVER, OF INDIANAPOLIS, INDIANA, ASSIGNOR, BY MESNE ASSIGNMENTS, TO IRA T. SWARTZ, TRUSTEE, OF INDIANAPOLIS, INDIANA.

CARBURETOR.

Application filed September 3, 1921. Serial No. 498,336.

This invention relates to carburetors, and the prime feature of the invention is the provision of means for controlling the admission of air into the carburetor and causing 5 the same to commingle with the fuel in proper proportion.

A further feature of the invention is the provision of a movable venturi adapted to be automatically positioned for controlling 10 the admission of air in accordance with the speed or running condition of the engine.

A further feature of the invention is the provision of means for adjusting or limiting the movement of the venturi.

15 A further feature of the invention is the provision of means for conveying air into the fuel chamber of the carburetor for aerating and agitating the fuel and for controlling the float when an excessive vacuum is 20 created in the upper portion of the carburetor.

Other objects and advantages will be hereinafter more fully set forth and pointed out in the accompanying specification.

25 In the accompanying drawings,

Figure 1 is a vertical transverse sectional view through the carburetor,

Figure 2 is a horizontal sectional view on line 2—2 Figure 1, and

30 Figure 3 is an enlarged top plan view of the tube employed for controlling the speed of the engine when running idle or at a low speed.

Referring to the drawings, 1 indicates the 35 bowl portion of the carburetor and 2 indicates the dome therefor, the bowl 1 having an air passage 3, one end of which extends through the wall of the bowl and the opposite end formed into a vertically extending collar 4.

40 The dome 2 is also provided with a collar 5, and the dome and bowl are connected together by means of a tube 6, the opposed ends of which are threaded into the collars 4 and 5 respectively.

45 The wall of the tube 6 is provided with series of ports or openings 7 through which vaporized fuel passes from the interior of the dome 2 into the tube 6 where it is commingled with air entering through the air 50 passage 3 and fuel entering the tube 6 through a nozzle 8.

For controlling the passage of the air from the air passage 3 into the tube 6, a venturi 9 is mounted within the tube 6 and is 55 vertically movable therein, the venturi being

automatically elevated co-incident to the degree of vacuum created by the engine to which the carburetor is attached, and by providing the ports 7 for the vaporized fuel in series the venturi will gradually close 60 the ports 7 as the venturi ascends in the tube 6 thereby limiting the amount of vaporized fuel entering the tube for maintaining the fuel at the proper richness.

Surrounding the discharge end of the 65 nozzle 8 is a secondary tube 10, the lower end of which is threaded onto the nozzle 8 and is spaced from that part of the nozzle entering the tube to provide an air chamber 11, the wall of the tube 10 at a point below 70 the discharge end of the nozzle 8 having openings 12 therethrough for the admission of air. The tube 10 is provided adjacent its upper end with a head 13, the upper face of which is shaped to fit within the lower end 75 of the venturi 9, so that when said venturi is in a lowered position, as when the engine is idling or running at low speed, the venturi and head will act as a valve for cutting off the major portion of the supply of air 80 through the air passage 3. It is preferable, however, to admit a limited amount of air through the venturi at all times, and for this purpose the peripheral edge of the head 13 is provided with vertically extending 85 channels 14 which are so located that the venturi will not close them when seated on the head, and a limited amount of air will pass through these channels.

In addition to forming air passages, the 90 channels 14 serve as slots for engagement with a spanner wrench, or tool of any class, as when the tube 10 is being attached to or removed from the nozzle 8. The lower end of the nozzle 8 is threaded through an opening in the wall of the air passage 3, and has communication with the fuel chamber in the bowl 1, a needle valve 15 being employed for controlling the passage of the fuel through the nozzle, the lower end of the valve 15 being projected through the wall of the bowl 1 so that the needle may be readily adjusted from the exterior of the carburetor.

The upward movement of the venturi 9 105 may be limited by any suitable means, but preferably by introducing a pin 16 transversely through the tube 6 at a distance above the normal position of the venturi when closed, and the downward movement 110

2
of the venturi may also be regulated for controlling its position relative to the head 13 by means of an adjusting rod 17, said rod being threaded through a bearing 18 formed between the inner wall of the bowl 1 and the outer wall of the air passage 3. For convenience of adjusting the rod the lower end thereof is projected a distance exteriorly of the bowl so that it may be 10 readily operated from the exterior of the carburetor, and it will readily be seen that by rotating the rod 17 so as to cause the same to move upwardly the venturi may be raised off the head 13 for increasing the 15 volume of air passing between the head and the venturi when the venturi is in closed position, and by properly adjusting the rod 17 the volume of air may be readily increased or decreased. After the rod 17 has 20 been properly adjusted it is held in its adjusted position by providing a milled-head or button 19 at the outer end of the rod with which engages a spring clip 20 for holding the head and rod against casual 25 rotation.

As is common in carburetors of this class, a float 21 is pivotally mounted within the fuel chamber of the bowl 1, which float controls the admission of fuel into the bowl 30 and in the event of an increase of vacuum within the upper portion or dome of the carburetor it sometimes happens that the float will not act with sufficient rapidity to prevent an over supply of fuel being 35 drawn into the fuel chamber, and to overcome this objectionable feature and at the same time agitate and aerate the fuel a by-pass 22 is formed through the wall of the bowl 1 and through a web 23 interiorly 40 of the bowl, the inner end of the by-pass being positioned in line beneath the float 21 so that the air passing through the by-pass will strike the float and cause the same to more rapidly elevate for cutting off the 45 supply of fuel entering the bowl. The opposite end of the by-pass terminates exteriorly of the bowl 1 and is interiorly threaded to receive a regulating cap 24 and by adjusting said cap vertically the volume 50 of air entering the by-pass may be increased or decreased.

With the present device, when the throttle of the engine is open and the engine started, the vacuum created in the dome portion of 55 the carburetor will automatically lift the venturi and move the same away from the head 13, the degree of upward movement of the venturi depending entirely upon the degree of vacuum created in the dome.

60 Having thus fully described my said invention, what I claim as new and desire to secure by Letters Patent, is:

1. In a carburetor, a fuel chamber, an air passage extending through the chamber, a 65 nozzle in the air passage, a passage from the

fuel chamber through the nozzle, a venturi at the upper end of the nozzle freely movable in the space between the nozzle and the wall of the air passage for controlling the passage of air through said air passage, a 70 head about the nozzle having a seat for the venturi, air passages in the periphery of the head leading past said venturi at regular intervals about the head, air passages extending through the head to the nozzle below said 75 seat, a mixing chamber above the nozzle, passages in the wall of the mixing chamber connecting it with the fuel chamber above the fuel level, said passage being controlled by said venturi, means for adjusting the venturi axially, and means for limiting the upward movement thereof, substantially as set forth.

2. In a carburetor, a fuel chamber, an air passage extending through the chamber, a 80 nozzle in the air passage, a passage from the fuel chamber through the nozzle, a venturi at the upper end of the nozzle freely movable in the space between the nozzle and the wall of the air passage for controlling the 85 passage of air through said air passage, a head about the nozzle having a seat for the venturi, air passages at regular intervals about the periphery of the head leading past 90 said venturi, air passages extending through the head to the nozzle below said seat, a mixing chamber above the nozzle, passages in the wall of the mixing chamber connecting it with the fuel chamber above the fuel level, said passage being controlled by said venturi, and means for adjusting the venturi axially, substantially as set forth.

3. In a carburetor, a fuel chamber, an air passage extending through the chamber, a nozzle in the air passage, a passage from the fuel chamber through the nozzle, a venturi at the upper end of the nozzle freely movable in the space between the nozzle and the wall of the air passage for controlling the 105 passage of air through said air passage, a head about the nozzle having a seat for the venturi, air passages at regular intervals about the periphery of the head leading past 110 said venturi, air passages extending through the head to the nozzle below said seat, a mixing chamber above the nozzle, and passages in the wall of the mixing chamber connecting it with the fuel chamber above the fuel level, said passage being controlled by said venturi, substantially as set forth.

4. A charge forming device comprising a fuel chamber, an air passage leading to an internal combustion engine and having passages forming communication with the fuel chamber above the level of the fuel, a spray nozzle extending into said air passage, means for admitting air beneath the level of the fuel in said fuel chamber, said air passage and passages forming communication with the fuel chamber above the level of the fuel 125 130

being open at all times to the suction of the engine, and a slideable venturi for partially closing said passages and for controlling the passage of air through said air passages, substantially as set forth.

5. A carburetor comprising a fuel chamber, means for maintaining the same partially filled with fuel, an air passage associated with the fuel chamber means for spraying fuel into said air passage, a passage for admitting air into the fuel chamber below the fuel level, means forming communication between the fuel chamber above the fuel level and the first mentioned air passage and a slideable venturi for controlling the air through the first mentioned air passage and through said communicating means, substantially as set forth.
6. The combination in a carburetor of a fuel chamber, a float for maintaining fuel in said chamber at a substantially constant level, a primary air passage associated with the fuel chamber, a secondary air passage, means for spraying fuel from the fuel chamber into the primary air passage, a passage for admitting air into the fuel chamber below the fuel level, communicating means

between the fuel chamber above the fuel level and the secondary air passage, a moveable venturi for regulating the amount of air through the secondary air passage and through the communicating means, substantially as set forth.

7. The combination in a carburetor of a fuel chamber, a float for maintaining said chamber partially filled with fuel, an air passage, means for spraying fuel from the fuel chamber into the air passage, a submerged blast, communicating passages between the fuel chamber above the level of the fuel and the air passage whereby atomized fuel may pass directly from the upper portion of the fuel chamber directly into the air passage and a slideable venturi for controlling the passage of air through the air passage and from the upper portion of the fuel chamber into said air passage, substantially as set forth.

In witness whereof, I have hereunto set my hand at Indianapolis, Indiana, this 13th day of August, A. D. nineteen hundred and twenty-one.

ALBERT E. WEAVER.
